Thomas P. Black

UNITED STATES PATENT OFFICE.

THOMAS P. BLACK, OF HOBOKEN, NEW JERSEY.

DESIGN FOR TEXTILE FABRIC.

No. 37,751.

Specification for Design.

Patented Dec. 19, 1905.

Application filed September 6, 1905. Serial No. 277,184. Term of patent 3½ years.

To all whom it may concern:

Be it known that I, THOMAS P. BLACK, a citizen of the United States, residing at Hoboken, in the county of Hudson and State of New Jersey, have invented a new, original, and ornamental Design for Textile Fabrics, of which the following is a specification, reference being had to the accompanying drawing, forming part thereof.

The drawing shows my design as applied to a textile fabric.

I claim—

The ornamental design for a textile fabric as shown.

THOMAS P. BLACK.
